(57) **CLAIM**

I claim the ornamental design for a trampoline, as shown and described.

DESCRIPTION

The file of this patent contains at least one drawing/photograph executed in color. Copies of this patent with color drawing(s)/photograph(s) will be provided by the office upon request and payment of the necessary fee.

FIG. 1 is a perspective view of a trampoline in accordance with the present design.

FIG. 2 is another perspective view of the trampoline shown in FIG. 1.

FIG. 3 is a front side view of the trampoline shown in FIG. 1.

FIG. 4 is a rear side view of the trampoline shown in FIG. 1.

FIG. 5 is a left side view of the trampoline shown in FIG. 1.

FIG. 6 is a right side view of the trampoline shown in FIG. 1.

FIG. 7 is a top view of the trampoline shown in FIG. 1; and, FIG. 8 is a bottom view of the trampoline shown in FIG. 1.
